UNITED STATES PATENT OFFICE

166,529

FONT OF TYPE

Wallace B. Conant, Concord, Mass.

Application October 30, 1950, Serial No. 12,782

Term of patent 14 years

(Cl. D64—12)

To all whom it may concern:

Be it known that I, Wallace B. Conant, a citizen of the United States of America and residing at Concord, county of Middlesex, Commonwealth of Massachusetts, have invented a new, original, and ornamental Design for a Font of Type, of which the following is a specification, reference being had to the accompanying drawing, forming part thereof.

The drawing illustrates face views of a font of type, showing my new design.

I claim:

The ornamental design for a font of type, as shown.

WALLACE B. CONANT.
